ALLAN GREEN, OF SUTTON, NEAR KEIGHLEY, ENGLAND

APPARATUS FOR USE IN THE PRODUCTION OF THREADS OF HAIR AND LIKE FIBERS

Application filed April 22, 1929, Serial No. 357,025, and in Great Britain April 23, 1928. Renewed January 26, 1932.

In the production of continuous threads and of woven fabrics composed of hair (such as horse hair which as is well known cannot be spun into a continuous thread except by the addition of other kinds of fibers) the great difficulty encountered is the selecting and separating of single hairs or a plurality of hairs from a bundle of same in order that said selected and separated hairs may be passed forward to feeding rollers when same have to be supplied to machines for spinning or encircling said hairs with other threads of fibrous substances (such as cotton and the like).

My present invention consists in the production of gripping devices which are operated in such a manner as to lay hold of a single hair or a plurality of hairs as same may be arranged so to do and when so laid hold of to cause said hairs to advance to be gripped by feeding rollers or grippers as above referred to. The said devices which I employ are of a character which enables them with the greatest regularity to select and separate the hairs as desired and under such conditions that said selected and separated hairs are carried forward when moved by the feeding devices so far that their rear ends are approaching the leading ends of the supply of hair, by which means the next succeeding hair or hairs that is or are being fed, is or are so presented to the feeding rollers, that portions of the extremities of the hairs overlap or slightly overlie each other thus ensuring the compounded thread to have a continuous core of hair.

In order that my said invention may be readily understood I have hereunto appended sheets of drawings illustrative thereof to which by figures and letters reference is made in the following description:—

Fig. 1 is a sectional end elevation of a machine or apparatus having devices constructed and arranged in accordance with my invention.

Fig. 2 is a front elevation of the parts shown by Fig. 1 and as seen looking from right to left of said figure.

Fig. 3 is a plan of the devices shown by Figs. 1 and 2.

Fig. 4 is a plan drawn to an enlarged scale of the holder or container and parts in connection therewith for receiving and containing bundles of hair from which single or a plurality of hairs has or have to be selected. 55

Fig. 5 is a front elevation of the devices shown by Fig. 4, and drawn to the same scale.

Figs. 6 and 7 are rear elevation and end elevation of the container shown by Fig. 5 and are drawn to the same scale. 60

Figs. 8 and 9 are plan and side elevation of selecting devices constructed in accordance with my invention.

Figs. 10 and 11 are similar views to Figs. 8 and 9 respectively but illustrate a modification hereinbefore described. 65

Figs. 12 and 13 are also similar views to Figs. 8 and 9 but show a further modification and parts operating in connection therewith.

Fig. 14 is a similar view to Figs. 8, 11 and 12 but shows means whereby the grippers may be normally closed and are opened by the guides. 70

Fig. 15 is an end elevation of devices I employ for varying the pressure on the bundle 75 of hairs within the container.

Figs. 16 and 17 show the formation of the gripping parts and devices in connection therewith for regulating the space between them for receiving the hair. 80

A A¹ indicates the end frames of the machine.

In carrying my invention into effect I make use of a receptacle 2 (which is preferably detachable from its supports 2a) into 85 which bundles of hair are placed so that same will occupy vertical positions therein with the lower ends of the hairs in the position shown at 3 of Fig. 6.

This container 2 has a slot 2a formed in its rear wall so that a lever 4 may extend crosswise to enter the container. This lever is fixed upon the lower end of a vertical spindle 4d which has another lever 4a fixed upon its upper end. The lever 4a has its 90 rearwardly extending arm 4f actuated by a spring 4b which normally presses the arm 4 against a sliding block 4g which moves over flanges 2s formed within the container 2. 95

The pressure of the block 4g carries the 100

bundle of hairs 3 against the curved and tapering end 2b of the container 2. By which means the end part 2b of the container presents the outermost hairs of the bundle of hairs 3 in suitable positions to enable the selecting member 5 to engage with them as is hereinafter explained.

The devices which form my selecting member 5 consist of jaws or gripping parts 5a and 5b. The part 5a is preferably slotted so that the part 5b may take into said slot where it is pivoted by a pivotal pin 6 (which also acts as a fixing screw), and where it is normally kept open (as shown by Fig. 8) by means of a spring 7 which is mounted within the slot in which the member 5b is also mounted.

The body part 5a which is slotted is made to fit a bifurcated holding member 8 which, by being split and having an extended slot 8a, is enabled to grip the body part 5a when the screw 8b is tightened to cause the bifurcation on each side to press against the member 5a.

This gripping member 8 forms the lower end of a lever 8c which is pivoted at its upper end 8d upon a lever 9.

The lever 9 is fixed upon a cross shaft 10 upon which shaft 10 is also fixed a lever 11 having a groove 11a formed in it to receive a sliding member 12 which is actuated by a crank pin 12a carried by a disc 12b. This disc 12b is fixed upon a shaft 13 which is supported by a bracket 14 mounted to be adjustable about the shaft 17 but held by the end frame A of the machine so that said shaft 13 may have fixed upon it a wheel 15 to gear or mesh with a wheel 16 fixed upon the shaft 17 which extends lengthwise the machine. The wheel 16 meshes with the wheel 17a which derives its motion from the wheel 17b which is fixed upon the shaft 17d which carries all the driving gripping rollers 30.

On the shaft 17d a wheel 31 is fixed and arranged to mesh with a wheel 31a fixed upon the hub of a three speed cone or driving pulley 17f which derives its motion through any appropriate driving belt.

By the use of the several parts described as the shaft 17 rotates to transmit motion to the disc 12b and therefore to the crank pin 12a the rotations of said crank pin transmit oscillatory motion to the arm 11 which is fixed upon the shaft 10 so that from this shaft 10 the same oscillatory motion may be transmitted to the lever arm 9 and therefore to the vertical lever 8c which carries the selecting member 5 as is hereinbefore described.

To the same pendant lever 8c is pivoted at 8f a connecting rod 18 and this connecting rod 18 is pivoted at 18a upon the pendant arm of a lever 19. The lever 19 is fixed upon a shaft 20 to which is fixed at the opposite end of the machine, a lever 21 and this lever

21 is retained in its normal position by its spring 21a while a roll 21b (carried by the upper arm 21s of said lever 21) is made to remain in contact with the cam surface 22 on a cam that is fixed upon the shaft 17.

By these means as said shaft revolves to transmit oscillatory motion to the arm 11 (in order to raise the lever 8c, which rising is permitted by a joint 18k in the rod 18, and also the selecting member 5) the cam 22 revolves and (through the lever 19) actuates the connecting rod 18 in order to transmit oscillatory motion to the lever 8c and therefore to cause the selecting member 5 to advance towards the hair 3 and recede from same as will be understood. The said advancing and receding motions are transmitted thereto in unison with the ascending and descending motions of the lever 8c, consequently by the actions of the crank 12a the selecting device is raised to its highest position and is kept during its rising movements in its rear position out of the path of the bundle of hair 3. On reaching its highest position said selector then commences to descend and when descending on reaching the desired position one or other of the cam surfaces 22a on the cam 22 actuates the lever 19 to cause said selector 5 to advance towards the hairs 3 there to engage with said hair as is hereinafter described.

In order to guide the member 5 in its vertical path I make use of the two guiding members 23 and 23a which extend vertically to have their upper ends fixed to a curved flat spring 24 as shown by Fig. 5. These guiding arms 23 and 23a are forced towards each other by means of a spring 25 (Fig. 5) so that they will retain their proper relative positions to guide the member 5 as it rises vertically when actuated as is hereinbefore described.

When the lever 8c is raised vertically on reaching its highest position the selector device begins to advance so that the outer ends of the parts 5a and 5b are brought to engage with the bundle of hairs 3 within the container 2. At the time that the gripper 5 is thus advancing, the spring 7 will have retained the leading space at w open so that a single hair (or plurality of hairs if so adjusted as hereinafter explained) will enter the said notch w shown by Fig. 8. When thus advanced to the desired distance the extension 5c at the rear end of the member 5b will pass through an inclined portion at 23d on the guide 23 (see Figs. 5 and 8) and will be thereby compressed thus overcoming the spring 7 and causing the outer end 5b to grip the hair between it and outer end of the member 5a.

When the hair is thus being gripped the selector 5 will descend carrying with it the hair that is gripped in an approximately straight path so that the lower end of the hair

130

is made to pass into the nip α (Fig. 1) between the rollers 30 and 30 a , and on being gripped by the rollers it is immediately released by the selector. The roller 30 which is fixed to or forms parts of the shaft 17 d is the driving roller while the roller 30 a is the driven roller which rollers carry the hairs that they grip in a vertical direction to pay same out as is hereinafter explained.

10. Arranged in conjunction with the rollers 30 and 30 a is a supply bobbin or other device for supplying thereto a thread of yarn which may be cotton or the like so that as the rollers 30 and 30 a revolve the thread of yarn supplied thereto is continuously fed downward along with the hair that is also fed to the nip of the same rollers 30 and 30 a .

As means for regulating the selector to effect the supplying of longer and shorter hairs, the number of cam parts 22 a is decreased or increased as is demanded by the number of deliveries as for example should four of the cam parts 22 a be carried, then for each revolution of the cam, four lengths or separate supplies of hairs would be carried, whereas provided only one cam part 22 a was employed then only one supply would be carried out at each revolution and the hair supplied would be correspondingly of greater length. The reduction or increase in the number of engagements of the cam parts 22 a does not interfere with the actions of the other movement of the selector, but allows same to continue its ordinary rising and descending actions without said selector being brought forward to select and detach any of the hairs until the cam parts 22 a causes it so to do. By these means the changing from the use of one length of hairs to another is effected without requiring any alterations to be carried out in connection with the other operating parts of the machine.

The hairs and the thread passing between the rollers 30 and 30 a are caused to descend through a hollow spindle 34 and upon this hollow spindle 34 is a bobbin of yarn or thread 32 which is loosely mounted thereon so that the same may be acted upon as is hereinafter described.

Fixed to the spindle 34 is a driving wharle or pulley 33 which derives its rotary motion from a driving band or tape actuated by the usual driving mechanism used in ordinary spinning machines.

The rotary motions of the wharle 33 are transmitted by it to the spindle 34, therefore by the thread 32 a being taken from the bobbin 32 over the splayed end of the spindle 34, as said spindle 34 revolves it will carry the thread 32 a around the thread α^1 and the hairs that accompany said thread. In this manner the thread from the bobbin 32 is wound around the thread and its hairs in order to enclose and bind same together.

As the compounded thread α^1 leaves the lower end of the hollow spindle 34 it is conducted to be wound on to a bobbin, spool or into the form of bundles of yarn by any ordinary well known type of apparatus for carrying out such winding actions.

I have found it desirable that the bundle of hairs should be slightly pressed in the opposite direction to that in which the selector 5 moves when approaching to engage said hairs so that by being thus pressed the selector is better fed with its supply of hair because if left undisturbed except by the selector the hairs in the bundle become pressed to one side or the other by the selector and therefore are not laid hold of with that certainty that I desired.

For this purpose I make use of a lever 35 the lower end of which has a projection 35 a which will press against the bundle of hairs at the part where they leave the holder or container 2. This lever 35 is of bell-crank type and is pivoted at 35 b to the end of a bracket 36. This bracket 36 is fixed upon the framework A while the horizontal arm of the lever 35 has an inclined end s for contact with a roll 8 g carried by the vertical lever 8 c .

After the lever 8 c has risen to the desired position it then commences to again advance towards the bundle of hairs 3 and on thus advancing the lever 8 c carries the runner 8 g into contact with the inclined end s of the lever 35 and raises said lever thus causing the lower end 35 a to press the hairs as described while a spring 37 secures the return movement of the lever 35 when the roll 8 g returns or descends.

The lever 4 which operates the sliding member within the container 2 is fixed upon a vertical spindle 4 d .

When a supply of hairs has to be placed within the container 2 the attendant actuates the hand lever 4 a so that the lever 4 will withdraw the sliding block 4 b from the container. He will then remove the empty container 2 from its supports and replace same by another which is supplied with its load of hairs.

In cases where the bundle of hair has a tendency to become too firmly pressed by having the constant pressure of the spring 4 b acting upon it I arrange said spring 4 b to be coupled to the upper end of a lever 40 (see Fig. 15) and this lever 40 is pivoted upon a pivotal stud 41 so that upon its lower end a roll 42 may be in position for being operated by a cam 43. This cam 43 is fixed upon a shaft 44 which has motion transmitted to it from any suitable motor part of the machine, either by ordinary toothed gearing or by chain and sprocket wheels, so that same may be caused to rotate in the direction indicated by the arrow t . This cam 43 has the effect of firstly releasing the pressure by the hollow part 44 a allowing the roll 42 to

descend thereon and then to be forced outwardly and very firmly pressed by the part 44b acting upon the roll 42 as shown by Fig. 15 while when said portion 44b has passed the roll 42 the cam allows same to recede and retain the pressure in a desired normal condition for about half a revolution of the cam 43.

I have hereinbefore described the movements of the selector member 5 as following a path in which it may move approximately vertically downwards when feeding hairs to the rollers so that the projecting end of the hair will go direct to the nip of the rollers, 18 but I am aware that in certain conditions and for comparatively long hairs an ordinary rotary selector, having jaws of the character hereinbefore described with reference to the members 5a and 5b may be made use of.

20 When making use of my improved detector devices constructed and arranged as shown by Figs. 10 and 11 I make use of only one operating member 23b and this member 23b is arranged to take between a projection 25 5s which is secured to the jaw 5a and another projection 5t which extends from the jaw 5b in which case the spring 7s tends to keep the jaws open until the inclined part 5u of the projection 5t comes in contact with the guiding member 23b by which it is closed.

The formation of the jaws 5a and 5b may be further modified as shown by Figs. 12 and 13. In this case the jaw 5b is actuated or closed by the guiding member 23 having an 35 extending portion 23w to contact with a roll 5v which is pivoted upon said jaw 5b. Thus the member 23 is also enabled to positively close the jaw 5b as desired and in this case the member 23w is acted upon by a spring 100 40 and an adjusting screw 101 so that a desired yield at the proper time of grip may be given to the said parts during their quick or rapid movements.

As an alternative to the formation shown 45 by Figs 12 and 13 the jaw 5b may be positively held open by the guiding member 23b and when clear of said guiding member a spring 7t may cause it to be closed as shown by Fig. 14.

50 The jaws 5a and 5b may be regulated to be opened to a greater or less extent according to the thickness of hairs that they have to engage with and in connection with the said jaws 5a and 5b, when formed as shown by 55 Fig. 17, I may use an adjusting plate 102 shown by Figs. 8, 9 and 17. This may be adjusted in a position nearer to or farther from the outer end of the jaw 5b so that the space 60 between said outer end and the adjustable plate 102 may be arranged to receive two hairs or more than two hairs or only one hair as the case may be and this adjustment is effected by the adjusting screws 103 and 104 65 the latter being screwed by the adjusting

screws 103 and 104 the latter being screwed into the stud 6.

When comparatively large or thick hairs have to be engaged with as shown by Fig. 16 the outer end of the jaw 5b may be inclined to form a wedge shaped opening as I find that by so forming said parts the plate 102 may be dispensed with since the jaws of this form will not grip more than one hair because the surfaces of the jaws will be so far apart beyond the first hair that they grip as not to be able to grip any other.

Such being the nature of my said invention what I claim is:—

1. In apparatus for producing continuous threads by surrounding or wrapping hairs with threads formed of other fibers, jaws for selecting and removing single hairs or a plurality of hairs from a bundle of hairs, adjustable devices for enabling said jaws to select single hairs or a plurality of same, lever devices for actuating said jaws, a cam formed adjustable so that it may be made to actuate the jaws once or a plurality of times during each of its revolutions to meet the requirements of shorter or longer hairs, rotary rollers arranged to receive and convey the hairs delivered to them by the jaws, said rotary rollers also adapted to receive the yarn, a wrapping device associated with said rollers, a wrapping thread carried for said wrapping device, and means for encircling said wrapping thread around the hair and thread as it issues from said rollers.

2. In apparatus for producing continuous threads by surrounding or wrapping hairs with threads formed of other fibers, a container for receiving a bundle of hairs, spring actuated devices for pressing the hairs within the container, gripping jaws for selecting and removing single hairs or a plurality of hairs from said bundle of hairs, adjustable devices for enabling said jaws to select single hairs or a plurality of same, lever devices for actuating said jaws, a cam formed adjustable so that it may be made to actuate the jaws once or a plurality of times during each of its revolutions to meet the requirements of shorter or longer hairs, rotary rollers arranged to receive and convey the hairs delivered to them by the jaws, said rotary rollers also adapted to receive the yarn, a wrapping device associated with said rollers, a wrapping thread carried for said wrapping device, and means for encircling said wrapping thread around the hair and thread as it issues from said rollers.

3. In apparatus for producing continuous threads by surrounding or wrapping hairs with threads formed of other fibers, a container for receiving a bundle of hairs, spring actuated devices for pressing the hairs within the container, gripping jaws for selecting and removing single hairs or a plurality of hairs from said bundle of hairs, adjustable

devices for enabling said jaws to select single hairs or a plurality of same, lever devices for actuating said jaws, a cam formed adjustable so that it may be made to actuate the jaws once or a plurality of times during each of its revolutions, to meet the requirements of shorter or longer hairs, rotary rollers arranged to receive and convey the hairs delivered to them by the jaws said rotary rollers also adapted to receive the yarn, a wrapping device associated with said rollers, a wrapping thread carried for said wrapping device, and means for encircling said wrapping thread around the hair and thread as it issues from said rollers.

4. In apparatus for producing continuous threads by surrounding or wrapping hairs with threads formed of other fibers, a container for receiving a bundle of hairs, spring actuated devices for pressing the hairs within the container, gripping jaws for selecting and removing single hairs or a plurality of hairs from said bundle of hairs, adjustable devices for enabling said jaws to select single hairs or a plurality of same, lever devices for actuating said jaws, a cam formed adjustable so that it may be made to actuate the jaws once or a plurality of times during each of its revolutions to meet the requirements of shorter or longer hairs, devices whereby the bundle of hairs may be intermittently pressed and relieved of pressure, rotary rollers arranged to receive and convey the hairs delivered to them by the jaws, said rotary rollers also adapted to receive the yarn, a wrapping device associated with said rollers, a wrapping thread carried for said wrapping device, and means for encircling said wrapping thread around the hair and thread as it issues from said rollers.

5. In apparatus for producing continuous threads by surrounding or wrapping hairs with threads formed of other fibers, a container for receiving a bundle of hairs, spring actuated devices for pressing the hairs within the container, gripping jaws for selecting and removing single hairs or a plurality of hairs from said bundle of hairs, adjustable devices for enabling said jaws to select single hairs or a plurality of same, lever devices for actuating said jaws, a cam formed adjustable so that it may be made to actuate the jaws once or a plurality of times during each of its revolutions to meet the requirements of shorter or longer hairs, cam actuated lever devices for effecting the vertically reciprocating motions of the jaws, rotary rollers arranged to receive and convey the hairs delivered to them by the jaws, said rotary rollers also adapted to receive the yarn, a wrapping device associated with said rollers, a wrapping thread carried for said wrapping device, and means for encircling said wrapping thread around the hair and thread as it issues from said rollers.

6. In apparatus for use in the production of threads of hair and like fibers, gripping jaws for selecting and removing single or a plurality of hairs from a bundle of hairs, guiding devices for the jaws formed to permit a spring to open same, said spring, an inclined part on the guides to close the spring, means for opening and closing said jaws, rotary rollers associated with said jaws, means for actuating the jaws to feed said hairs to said rotary rollers, said rotary rollers also adapted to receive the yarn, a wrapping device associated with said rollers, a wrapping thread carried for said wrapping device, and means for encircling said wrapping thread around the hair and thread as it issues from said rollers.

7. In apparatus for producing continuous threads by surrounding or wrapping hairs with threads formed of other fibers, jaws for selecting and removing single hairs or a plurality of hairs from a bundle of hairs, an adjustable plate for limiting the length of the space between the jaws when open to enable said jaws to select single hairs or a plurality of same, lever devices for actuating said jaws, a cam formed adjustable so that it may be made to actuate the jaws once or a plurality of times during each of its revolutions to meet the requirements of shorter or longer hairs, rotary rollers arranged to receive and convey the hairs delivered to them by the jaws, said rotary rollers also adapted to receive the yarn, and devices for rotating the said yarn to surround said hairs.

8. An apparatus for use in the production of threads of hair and like fibers having in combination a container for receiving the bundle of hair to be selected, a selector having a pair of co-acting jaws, vertical guides for controlling the movement of said jaws, means for simultaneously reciprocating and imparting vertical movement to said jaws, means on one of said guides for actuating said jaws so as to selectively withdraw the hairs from the container, rollers adapted to receive the yarn and positioned beneath said container, a wrapping device, a wrapping thread carried by said wrapping device, and means for encircling said wrapping thread around the hair and thread as it issues from said rollers.

9. An apparatus for use in the production of threads of hair and like fibers having in combination a container for receiving the bundle of hair to be selected, a selector having a pair of co-acting jaws, vertical guides for controlling the movement of said jaws, means for simultaneously imparting vertical movement to said selector and for oscillating the jaws to move them towards and away from said receptacle, means for normally separating said jaws, means on one of said guides for closing the jaws when the latter are moved towards the container, rollers

- adapted to receive the yarn and positioned beneath said container, means for actuating said jaws for conducting the selected hairs through said rollers, a wrapping device, a wrapping thread carried by said wrapping device and means for encircling said wrapping thread around the hair and thread as it passes through the wrapping device.
10. An apparatus for use in the production of threads of hair and like fibers having in combination a container provided with a curved and tapered open end, and arranged to receive the bundle of hair to be separated, means for urging the bundle of hair towards said end, gripping jaws for selecting and removing single or a plurality of hairs from said bundle, means for moving said jaws vertically, means for reciprocating said jaws, vertically disposed guides for said jaws, means associated with said guides for opening and closing said jaws, rollers adapted to receive the yarn and positioned beneath said container, means for actuating said jaws for conducting the selected hairs to said rollers,
- 25 a wrapping device, a wrapping thread carried by said wrapping device, and means for encircling said wrapping thread around the hair and thread as it passes through the wrapping device.
- 30 11. An apparatus for use in the production of threads of hair and like fibers having in combination, a container provided with a curved and tapered open end, and arranged to receive the bundle of hair to be separated, means for urging the bundle of hair towards said end, gripping jaws for selecting and removing single or a plurality of hairs from said bundle, means for simultaneously reciprocating and imparting vertical movement to said jaws, vertically disposed guides for said jaws, means associated with said guides for opening and closing said jaws, rollers adapted to receive the yarn and positioned beneath said container, means
- 35 for actuating said jaws for conducting the selected hairs to said rollers, a wrapping device, a wrapping thread carried by said wrapping device, and means for encircling said wrapping thread around the hair and thread
- 40 as it passes through the wrapping device.
